FOUR-IN-HAND TIE KNOT HOLDER

William C. Wester, Springfield, Mo.

Application April 11, 1952, Serial No. 281,711

3 Claims. (Cl. 2—153)

1

This invention relates to four-in-hand tie knot holders and more particularly to a holder which is of assistance in tying a four-in-hand knot, and serves as a form to shape the knot and as a holder to restrain the knot against loosening.

It is among the objects of the invention to provide an improved four-in-hand tie knot holder which can be used to assist in neatly and quickly forming a four-in-hand knot; which holds the knot in shape and holds the tie against wrinkling in and below the knot; which permits the shorter end of the tie to slip freely through the knot so that the tie can be put on and taken off repeatedly without untangling the knot; which provides a four-in-hand knot of neat and attractive appearance; and which is simple and durable in construction, economical to manufacture, and effective and efficient in use.

Other important objects and advantages will become apparent from a consideration of the following description and the appended claims in conjunction with the accompanying drawing wherein:

Figure 1 is a perspective view of a four-in-hand knot formed on a knot holder illustrative of the invention looking toward the front side of the knot;

Figure 2 is a perspective view of the knot and holder illustrated in Figure 1 looking toward the rear side of the knot;

Figure 3 is a rear elevational view of the knot holder showing an initial step in tying a knot thereon;

Figure 4 is a view similar to Figure 3 showing a later step in the tying of the knot;

Figure 5 is a view similar to Figures 3 and 4 showing a still later step in the tying of the knot;

Figure 6 is a front elevational view of the knot holder showing a final step in the tying of a four-in-hand knot thereon; and

Figure 7 is a perspective view of the knot holder.

With continued reference to the drawing, the knot holder, as illustrated in Figure 7, is a body of resilient sheet material, such as a metallic or plastic sheet material and includes a portion 10 of somewhat trapezoidal shape having convexly curved non-parallel edges 11 and 12, a longer end 13 and a shorter end 14 substantially parallel to the longer end 13, the ends 13 and 14 both being generally symmetrical of the longitudinal center line of the trapezoidal portion of the sheet metal body.

The body portion 10 is transversely curved so that adjacent its longer end it has a C-shaped cross section with the curved edges 11 and 12

2

spaced from each other and spaced outwardly from the same side of the intermediate portion of the body. These curved edges fair into the intermediate portion of the trapezoidal part 10 of the body adjacent the shorter end 14 of the trapezoidal portion so that this shorter end has a flat arcuate curvature rather than a C-shaped curvature such as the cross sectional shape of the body adjacent the longer end of the trapezoidal portion.

An elongated tongue 15 having straight and substantially parallel side edges is joined at one end to the trapezoidal portion 10 substantially at the center of the longer end 13 of this portion and is longitudinally curved adjacent the longer end of the trapezoidal portion through an angle of approximately 180 degrees, as indicated at 16, so that it extends along and is spaced from the same side of the intermediate part of the trapezoidal portion 10 as that from which the curved edges 11 and 12 are spaced and is disposed between these curved edges. The distal end of the tongue 15 is disposed adjacent the shorter end 14 of the trapezoidal portion of the body and an arm 17 projects laterally from the tongue 15 at the distal end of the latter and this arm has at its distal end a hook formation 18 which engages the curved edge 12 of the trapezoidal portion 10 near the shorter end 14 of the trapezoidal portion to releasably secure the distal end of the tongue to the remainder of the body.

In tying a four-in-hand knot on the tie holder the hook formation 18 is first released from the curved side edge 12 of the transversely curved body portion 10 of the holder and a tie, as indicated at 20 is inserted in the holder under the tongue 15 with the longer end of the tie extending through the opening 21 at the longer end 13 of the body portion 10 between the proximal end of the tongue 15 and the curved side edge 12 of the body portion with the short end of the tongue extending past the shorter end 14 of the holder body. The longer end portion of the tie is then looped around and brought through the opening 22 between the proximal end of the tongue 15 and the curved side edge 11 of the body 10 and is brought under the tongue and disposed between the curvature 16 at the proximal end of the tongue and the arm 17 at the distal end of the tongue. This longer end of the tie is then folded back over the tongue 15 and carried around the outer surface of the holder body past the side edge 11 and to the side edge 12, as indicated at 23 in Figure 5.

Running the longer end of the tie under the

tongue 15 of the holder provides a loop 24 in the tie at the longer end 13 of the holder and the longer end of the tie is now carried past the curved side edge 12 of the holder body and inserted through the loop 24. The longer end of the tie is inserted under the portion 25 of the longer end which passes around the front outer surface of the holder body. The hook formation 18 is now re-engaged with the side edge 12 of the body 10 and the longer end portion of the tie is tightened around the holder, as shown in Figure 1.

The tie now covers the entire front surface of the holder but the holder extends below the portion 25 of the tie extending around the holder, as indicated at 26, to avoid wrinkling of the depending longer end portion 21 of the tie below the knot formed on the holder. The loop 24 can be enlarged by pulling the end of the tie through the holder outwardly of the longer end 13 of the holder until it will pass over the wearer's head. After this loop has been inserted in a shirt collar, it can be easily tightened by merely pulling the shorter end of the tie through the holder inwardly of the longer end 13 and outwardly of the shorter end 14 of the holder.

The passing of the longer end of the tie over the portion of the loop 24 at the longer end of the holder, as indicated at 28, serves as a binder for holding the loop in adjusted position after it has been adjusted in size to the shirt collar, this binding action being obtained by merely pulling the longer end portion of the tie downwardly through the portion 25 looped around the holder.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A four-in-hand tie knot holder comprising a body of resilient sheet material including a portion of somewhat trapezoidal shape having convexly curved non-parallel edges and transversely curved to a C cross sectional shape adjacent its wider end, an elongated tongue joined at one end to said trapezoidal portion adjacent the center of the longer end of the latter and being longitudinally curved through an arc of approximately one hundred and eighty degrees near said one end so that a portion thereof is disposed between the convexly curved edges of said trapezoidal portion, an arm projecting laterally from said tongue at the other end of the latter, and a hook formation on the distal end of said arm engaging the adjacent convexly curved edge of said trapezoidal portion near the shorter end of

the latter to releasably secure said tongue at its distal end to said trapezoidal portion.

2. A four-in-hand tie knot holder comprising a body of resilient sheet material including a portion of somewhat trapezoidal shape having convexly curved non-parallel edges and transversely curved to a C cross sectional shape adjacent its wider end, an elongated tongue joined at one end to said trapezoidal portion adjacent the center of the longer end of the latter and being longitudinally curved through an arc of approximately one hundred and eighty degrees near said one end so that a portion thereof is disposed between the convexly curved edges of said trapezoidal portion, an arm projecting laterally from said tongue at the other end of the latter, and a hook formation on the distal end of said arm engaging the adjacent convexly curved edge of said trapezoidal portion near the shorter end of the latter to releasably secure said tongue at its distal end to said trapezoidal portion, the convexly curved edges of said trapezoidal portion fairing into the intermediate portion of the latter near the respectively opposite ends of the shorter end edge of said trapezoidal portion.

3. A four-in-hand tie knot holder comprising a body of resilient sheet material including a portion of somewhat trapezoidal shape having convexly curved non-parallel edges and transversely curved to a C cross sectional shape adjacent its wider end, an elongated tongue joined at one end to said trapezoidal portion adjacent the center of the longer end of the latter and being longitudinally curved through an arc of approximately one hundred and eighty degrees near said one end so that a portion thereof is disposed between the convexly curved edges of said trapezoidal portion, an arm projecting laterally from said tongue at the other end of the latter, and a hook formation on the distal end of said arm engaging the adjacent convexly curved edge of said trapezoidal portion near the shorter end of the latter to releasably secure said tongue at its distal end to said trapezoidal portion, the convexly curved edges of said trapezoidal portion fairing into the intermediate portion of the latter near the respectively opposite ends of the shorter end edge of said trapezoidal portion and said tongue having straight and substantially parallel side edges with said arm extending substantially perpendicularly from the tongue at the distal end of the latter.
